[57] CLAIM

The ornamental design for a bread slicing rack, as shown and described.

DESCRIPTION

FIG. 1 is a perspective view of a bread slicing rack showing my new design;

FIG. 2 is a right side view thereof with the end plate portions removed for clarity of illustration, the left side view being a mirror image;

FIG. 3 is a front view of FIG. 2, the rear view being a mirror image;

FIG. 4 is a top plan view of FIG. 2;

FIG. 5 is a bottom plan view of FIG. 2;

FIG. 6 is a left side view of the end plate portion shown separately for clarity of illustration;

FIG. 7 is a right side view of FIG. 6;

FIG. 8 is a rear view of FIG. 6;

FIG. 9 is a top plan view of FIG. 6; and,

FIG. 10 is a bottom plan view of FIG. 6.
